United States Patent Office

Des. 228,406

Patented Sept. 18, 1973

228,406

CLOCK HOUSING

Richard K. Thomas, Elk Grove Village, Ill., assignor to
Sunbeam Corporation, Chicago, Ill.

Filed Dec. 29, 1971, Ser. No. 213,797

Term of patent 14 years

Int. Cl. D10—01

U.S. Cl. D42—7 R

Fig. 1.

Fig. 2.

Fig. 3.

Fig. 4.

FIG. 1 is a front elevational view of a clock housing showing my new design;

FIG. 2 is a top plan view thereof;

FIG. 3 is a right side elevational view thereof, the left side being a mirror image thereto;

FIG. 4 is a sectional view taken from line 4—4 of FIG. 1.

I claim:

The ornamental design for a clock housing, as shown and described.
